UNITED STATES PATENT OFFICE.

HEINRICH DEGENER, OF BERLIN, GERMANY, ASSIGNOR TO MERGENTHALER LINOTYPE COMPANY, A CORPORATION OF NEW YORK.

TYPOGRAPHICAL LINE-CASTING MACHINE.

1,006,445.

Specification of Letters Patent. Patented Oct. 17, 1911.

Application filed August 25, 1911. Serial No. 646,012.

To all whom it may concern:

Be it known that I, HEINRICH DEGENER, a subject of the German Emperor, residing at 26 Hollmannstrasse, Berlin, in the German Empire, have invented new and useful Improvements in Typographical Line-Casting Machines, of which the following is a specification.

This invention relates to typographical line-casting machines such as those known commercially under the trade mark "Linotype" and particularly to those machines which are provided with circulating matrices each of which has two formative cavities, one above the other. In these machines, when it is desired to compose what is known as a mixed line, that is to say, a line composed of letters of both the upper and lower formative cavities, the matrices of a composed line must be supported in the first elevator at two different levels so as to present the respective upper and lower formative cavities all in the same casting line. This result has heretofore been attained by means of a rail or ledge movable into and out of the channel of the first elevator, this ledge being projected into the said channel for supporting the matrices in the upper position therein during the casting operation, and withdrawn therefrom to allow those matrices to descend to the common level preparatory to distribution. In consequence of the ledge being movable, and thereby causing wear between the relatively movable surfaces, it cannot be relied upon, as it should be, to secure true alinement of the formative cavities. Attempts have already been made to obviate this difficulty by providing a fixed rail or ledge in the first elevator, and, before distribution, bringing the matrices to their common lower level by a curved or inclined guide or cam against which they are caused to act when being moved out of the first elevator. This, however, has resulted in the rapid wearing of the matrices, as the guide was very short, and the curve or incline thereof very abrupt.

According to the present invention the first elevator, besides being provided with a fixed rail or ledge as heretofore, is also provided with means which enable the feet of all the matrices to be brought to a common level before the said matrices are pushed out of the first elevator.

In the accompanying drawings, which show two constructional forms of the im-

proved mechanism, Figure 1 is a fore-and-aft section through the head of the first elevator with the matrices still in the casting position therein, and the said first elevator just approaching its highest position; Fig. 2 is a view similar to Fig. 1 but showing the first elevator with the matrices released and free to descend to the common level; Fig. 3 is a view also similar to Fig. 1 but showing the first elevator in its highest position; Fig. 4 is a plan of the first elevator, and Fig. 5 is part of a front view thereof; Figs. 6 and 7 are diagrammatic views showing the means for widening the channel of the first elevator; and Figs. 8, 9, 10 and 11 are views respectively corresponding to Figs. 4, 5, 6 and 7 of a second constructional form of the devices.

The first elevator head consists of two walls 1 and 2, of which the latter is guided in the former by a bar 3 whose forward end is provided with a double cam 4, as shown best in Figs. 6 and 7, which projects to the front of the part 1. Two tension springs 5 normally hold the two parts of the first elevator head together. The known ledge 6 arranged on the part 1, which serves to support the matrices in the lower position, is, as distinguished from other arrangements, movable horizontally in a fore-and-aft direction. It is guided in the part 1 and pressed by springs 7 (only one of which is shown) toward the rear of the first elevator. The springs 7 each encircle a rod 8 provided with a nut or head 9 which limits the action of the respective spring. The ledge 10, on which the matrices stand when assembled in the upper position, is fixed. A cam or projection 11 is fixed on the frame 95 of the machine, in position to engage with the before described cam 4 when the first elevator is approaching its uppermost position.

The operation of the first elevator is as follows: After the line has been composed and a type-bar cast therefrom in the known way, the first elevator is moved to its uppermost position preparatory to distribution of the matrices. During this upward movement of the first elevator the cam 4 comes into contact with the fixed cam 11, and is thereby pressed rearward as in Fig. 7, so that the channel of the first elevator head is widened and, at the same time, by the pressure of the springs 7, the ledge 6 is similarly pushed rearward as in Fig. 2. The matrices which

- were composed in the higher position thereby lose their support and fall by gravity into the position shown in dotted lines in Figs. 1 and 2. On the further upward movement of the casting slide the cam 4 passes the stationary cam 11, the part 2 of the first elevator, under the tension of the springs 5, returns to its forward position, and the matrices all being now at a common level as 10 in Fig. 3, can be pushed on to the toothed rail of the second elevator which raises them to the distributor. The known depressor rail 12, which presses on the upper part of the matrices, can also be used.
- 15 The arrangement shown in Figs. 8 to 11 corresponds generally to the before described arrangement, but instead of the tension springs 5 for drawing the two parts 1^a, 2^a of the first elevator toward each other, 20 compression springs 13 are provided which constantly tend to push the two parts 1^a, 2^a farther from each other. The rear part 2^a of the first elevator has a projection 14, which slides along a rail 15 which is provided with a notch or cam 16. At the right moment the projection 14 enters the notch 16, as shown in Fig. 11, and the part 2^a will, in consequence thereof, be pushed rearward by the springs 13 to allow the higher matrices to descend to the level of the lower ones.

The ledge 6 being movable as aforesaid, in the first elevator, will be in its rearmost position so long as no matrices are in the 35 said first elevator, and the entering matrices must push it forward into the positions shown in Figs. 1 and 3. In order the better to secure this result, the end of the ledge with which the matrices first come into contact is rounded as shown at 17 in Fig. 4 and at 17^a in Fig. 8, so as, at that part, to form a cam.

Having thus described my invention, I declare that what I claim and desire to secure 45 by Letters Patent is:—

1. In a typographical line-casting machine, a first elevator having in combination front and rear walls forming between them a matrix-receiving channel, and means con-

necting the two said walls together so that 50 one wall can be moved toward and away from the other wall.

2. In a typographical line-casting machine the combination with a first elevator having relatively movable front and rear 55 walls forming between them a matrix-receiving channel, springs imparting this relative movement in one direction, and cam devices operative to impart the said relative movement in the other direction during the 60 travel of the first elevator to the distributing position.

3. In a typographical line-casting machine the combination with a first elevator having relatively movable front and rear 65 walls forming between them a matrix-receiving channel, springs imparting this relative movement in one direction, a cam fast to one of the walls, and a stationary cam in the path pursued by the first named cam 70 when moving to the distributing position to impart the said relative movement in the other direction.

4. In a typographical line-casting machine the combination with a first elevator 75 having relatively movable front and rear parts forming between them a matrix-receiving channel, a ledge for the matrices on one of the parts, movable relatively to that part to project more or less into the 80 channel, springs moving the said ledge in one direction, and a cam on the ledge in the path of the matrices to move it in the other direction.

5. In a typographical composing machine, 85 the first elevator formed with its opposite walls relatively movable.

6. In a typographical composing machine, the first elevator formed with its opposite walls relatively movable, combined with 90 means to move the said walls toward and from each other.

In witness whereof I have hereunto set my hand in the presence of two witnesses.

HEINRICH DEGENER.
